UNITED STATES PATENT OFFICE.

DAVID E. BOWN, OF PITTSBURGH, PENNSYLVANIA.

FUSE-PLUG.

1,298,654.

Specification of Letters Patent.

Patented Apr. 1, 1919.

Application filed April 25, 1918. Serial No. 230,654.

To all whom it may concern:

Be it known that I, DAVID E. BOWN, a resident of Pittsburgh, in the county of Allegheny and State of Pennsylvania, have 5 invented a new and useful Improvement in Fuse-Plugs, of which the following is a specification.

This invention relates to fuse plugs. The invention has for its object to provide a 10 fuse plug of simple construction and hence cheap to manufacture, which can be quickly and conveniently assembled at a minimum labor cost, which is so constructed that the fuse can be renewed when blown out without 15 destroying the body, and which possesses other advantages hereinafter described.

The invention comprises a fuse plug constructed as hereinafter described and claimed.

20 In the accompanying drawings, Figure 1 is a longitudinal central section of the improved fuse plug; Fig. 2 is a top plan view of the same; and Fig. 3 is a bottom plan view of the same.

25 As illustrated, the plug comprises an integral cup-shaped body portion 1, which can be formed of any suitable insulating material, such as the well known moldable or pressed compositions known in the electrical art, or fiber. The body is slotted vertically from its upper edge as at 3, to allow for the passage of the fuse wire 4 when assembling, and the bottom of this hollow body carries a center contact 2, which is 35 shown as a hollow rivet flanged both inside and outside of the bottom 2.

This cup-shaped body is closed by means of a cover 5 which is provided with a window 6 and which clamps against the upper 40 end of the body a suitable transparent dia-phragm 7, such as a disk of mica. The cover is provided with depending flanges 8 which surround and telescope the body and extend down toward but not quite to the bot-

45 tom of the vertical slot 3. The outer contact is in the form of a screw threaded shell 9 which is suitably secured to the depending flanges 8 of the cover, such as by means of the hollow rivets 10. The upper edge of 50 this shell is bent inwardly so as to be in firm contact with the outer surface of the body, and said edge is preferably serrated as shown at 11, so as to bite into the composition body and thereby firmly hold the 55 cover in assembled engagement with the body. The shell on one side below the flange

8 of the cover is provided with an opening 12 through which the end of the fuse wire projects. This fuse wire can be secured to the center contact in any suitable way, such as by means of soldering, as indicated at 13, and its other end is secured to the outer face of the screw shell adjacent to the opening 12, as at 14, in a similar way.

The fuse plug described is of very simple construction having a minimum number of parts, all of which can be conveniently fabricated and assembled. The body 1 and cover 5 are formed by simple molding or pressing processes, preferably from the composition above described, and are of relatively thin construction, thus requiring a minimum amount of material and forming a plug which is light but nevertheless strong. The center contact 2 is secured to the cup-shaped body before assembling by a simple upsetting process, and the screw shell 9 is also secured to the depending flanges 8 of the cover before assembling by a simple riveting process, after the mica disk 7 has been 80 glued in place. To assemble the plug, the fuse wire which will be on a spool will be threaded through the opening 12 in the shell, before the cover and body are assembled, its end then secured to the contact 2, after 85 which the body is slipped up into the shell and the cover brought tightly down against the mica disk. The excess length of fuse is then drawn outwardly through the opening 12 and the end of the portion in the 90 plug is pinched off and soldered at 14. The serrated upper edge of the shell bites into the walls of the body and holds the parts in firm assembled position. The connection of the fuse with the shell at 14 also assists 95 in holding the parts together.

The upper edge of the body is serrated, as indicated at 15, so as to allow for ventilation and the escape of the gases when the fuse blows.

What I claim is:—

1. A fuse plug comprising a cup-shaped body, a center contact carried by the bottom thereof, a cover for said body provided with a window and with depending flanges telescoping the body, a screw shell secured to said flanges and provided with an opening, and a fuse wire secured to the center contact and extending through the opening in the shell and secured thereto.

2. A fuse plug comprising a cup-shaped body, a center contact carried by the bot-

tom thereof, a cover provided with a window and with depending flanges telescoping the body, a screw shell secured to said flanges, the upper end of said screw shell being bent inwardly and provided with 5 prongs to engage the outer face of the body, and a fuse wire secured to the center contact and to the screw shell.

3. A fuse plug comprising a cup-shaped body, a center contact carried by the bottom thereof, a cover provided with a window and with depending flanges telescoping the body, and a screw shell secured to said flanges and provided with an opening 10 for the passage of the fuse wire, the upper end of said screw shell being contracted and firmly engaging the outer surface of said body.

4. A fuse plug comprising a cup-shaped body slotted from its upper end downwardly, a center contact carried by the bot- 15

tom of said body, a cover provided with a window and with depending flanges telescoping the body, and a screw shell secured to said flanges and provided with an 20 opening for the passage of the fuse wire.

5. A fuse plug comprising a cup-shaped body slotted from its upper end downwardly, a center contact carried by the bottom of said body, a cover provided with 25 a window and with depending flanges telescoping the body, and a screw shell secured to said flanges and provided with an opening for the passage of the fuse wire, the upper end of said screw shell being contracted and firmly engaging the outer surface of said body.

In testimony whereof, I have hereunto set my hand.

DAVID E. BOWN.

Witness:

GLENN H. LERESCHE.
